UNITED STATES PATENT OFFICE

WILHELM RUNGE, OF BERLIN, GERMANY, ASSIGNOR TO TELEFUNKEN GESELLSCHAFT FÜR DRAHTLOSE TELEGRAPHIE MIT BESCHRÄNKTER HAFTUNG, OF BERLIN, GERMANY, A CORPORATION OF GERMANY

ARRANGEMENT FOR OSCILLATION CIRCUITS

Application filed November 6, 1925, Serial No. 67,206. Renewed November 7, 1930.

The object of the invention is to provide means whereby the differential beat frequency resulting from two oscillation circuits is kept constant during equal changes in tuning means.

A further object of the invention is to provide means whereby at a single setting, for instance, the turning of a knob or handle, the beat frequency of two cooperating oscillation circuits preserves a constant magnitude.

Other objects of the invention will appear more fully hereinafter as shown in the accompanying drawing, and finally pointed out in the appended claims.

Referring to the drawing, Fig. 1 shows an embodiment of an arrangement conformable with the present invention.

Fig. 2 is a diagram showing a graph wherein the dependence of the resonance frequency of an oscillation circuit upon the reciprocal value of a capacity and their functions,—is exhibited.

Fig. 3 is a diagrammatic sketch wherein inductance values are substituted for the variable capacity. Fig. 4 shows the means for adjusting the variable condensers. In connection with the service work and the various problems encountered in high frequency work it is often essential that the difference in frequency of oscillations of two high frequency circuits should be kept constant over variable wave ranges. A change from one wave range to another wave range ordinarily requires separate setting of tuning means in each of the two circuits. In many cases separate adjustment of the tuning means in each of the circuits is rather tedious and inconvenient.

One of the problems to be solved by the present invention is that by a single setting as for example the turning of a knob or handle as set forth below the beat frequency of two oscillation circuits, which may be varied, is maintained constant. An illustrated embodiment

of the invention consists in that one of the two oscillation circuits is an inductance and a condenser of the rotary type, and the other oscillation circuit is an inductance of somewhat lower value, a rotary condenser, and a fixed condenser in series with the latter. It can be proved that with a proper proportioning of the circuits, a synchronous turning of the two condensers or other tuning elements may be made to yield a differential beat whose frequency remains appreciably constant. The circuits shown in Fig. 1 illustrate a self-inductance L_1 and a capacity C_1 , while the other circuit possesses a self-inductance of lesser value L_2 and a capacity which is determined by the series connection of the two condensers with capacities C_2 and C_3 .

In Fig. 2 the dependence of the resonance frequency of an oscillation circuit upon the reciprocal value of capacity (see curve 1),—is shown. This curve, as is well-known is the parabola. If in the same graph the dependence of frequency on

$$\frac{1}{C_s}$$

is plotted for the case where the oscillation circuit contains in addition the series capacity C_s , there results a displacement of the parabolic curve along the abscissa by an amount

$$\frac{1}{C_s}$$

as shown by curve 2, which constitutes a function of the frequency and

$$\frac{1}{C_s} + \frac{1}{C_s}$$

The shape of the parabola (its focal distance) depends itself upon the value of the self-inductance which represents the parameter. Hence, by a convenient selection of the self-inductance, it is easy to change curve 2

into curve 3. Curve 1, therefore, represents the frequency depending upon the change in capacity in an oscillation circuit such as circuit 1 in Fig. 1, and curve 3 shows the frequency dependence of an oscillation circuit corresponding to circuit 2, Fig. 1, upon the analogous setting of the corresponding rotary condenser in this circuit. Hence, the relation holding for the circuit 1 is

$$10 \quad \omega_1 = \sqrt{\frac{1}{L_1}} \cdot \sqrt{\frac{1}{C_1}}$$

and the relation for circuit 2 is

$$15 \quad \omega_2 = \sqrt{\frac{1}{L_2}} \times \sqrt{\frac{1}{C_1} + \frac{1}{C_2}}$$

As can be inferred from numerical examples and as diagrammatically shown in the graph, the difference of the frequencies of the two circuits inside a frequency range lying approximately between points A and B, is nearly constant. It is, therefore, possible by means of an arrangement of the kind shown and built in conformity with the basic idea 20 of the invention, to mount the two condensers upon a common axis or spindle and to vary the tuning in the two circuits by turning one knob in such a manner that the difference 25 of their frequencies remains well nigh unvaried. Figure 4 shows the two variable condensers C_v having their movable plates 1 mounted upon a common spindle 2 which is provided with an adjusting knob 3 at one end 30 for simultaneously adjusting the condensers. 35

A corresponding result is attainable also by other means, for example, in one of the circuits a variometer is exhibited in lieu of a rotary condenser, and instead of the fixed self-inductance coil a fixed condenser. Also 40 in circuit 2 in lieu of the series connection of the fixed and the variable condenser a parallel connection may be substituted consisting of a low and a high self-inductance. In an 45 arrangement of this kind the functions of L and C are exchanged as can be seen by comparison of the relations between the two circuits.

A very important application of the present 50 invention is in beat reception arrangements, for instance, telephone reception apparatus working with intermediate beat frequency. One of the oscillation circuits in this case is the circuit to which the incoming 55 high frequency oscillations are supplied while the second circuit is the oscillation circuit of the local high frequency generator whose oscillations are superposed upon the 60 incoming high frequency oscillations, rectification of the oscillatory currents being then made.

By a single adjustment it is then possible to effect the tuning of the radio receiving 65 circuit as well as to maintain constant the

beat frequency of the intermediate or differential frequency.

Having now set forth the object and nature of my invention what I claim as new and useful and desire to secure by Letters Patent is, 70

1. In a heterodyne receiving system, the combination of a receiving circuit and a local oscillation circuit, one of said circuits including an inductance, a fixed condenser and a variable condenser and the other of said 75 circuits including only an inductance and an equal variable condenser, said variable condensers being of substantially similar characteristics throughout the range of variation and common means for adjusting said variable condensers by equal amounts, the values of said fixed and variable condensers being so related that a beat frequency of substantially constant value is produced by adjustment of said variable condensers, the inductance in one of said circuits being greater 80 than the inductance in the other. 85

2. In a heterodyne receiving system, a receiving circuit including only an inductance and a variable condenser, a local oscillation circuit coupled to the receiving circuit including an inductance, a fixed condenser and a variable condenser connected in series, the capacities of said variable condensers being equal and said variable condensers being 90 equally adjusted by a common means, said fixed and variable condensers having such proportional values that a differential beat frequency of substantially constant value is produced as the receiving circuit is tuned, the inductance in the oscillation circuit being less 95 than the inductance in the receiving circuit. 100

3. A superheterodyne receiving arrangement comprising a receiving circuit and a local oscillation circuit, one of said circuits including an inductance, a fixed condenser and a variable condenser and the other circuit including an inductance and a variable condenser substantially equal to said first named 105 variable condenser, said variable condensers being of substantially similar characteristics throughout the tuning range and a single control means for adjusting said variable condensers by equal amounts, said fixed and variable condensers having such relative 110 values that a high intermediate beat frequency of substantially constant value is produced by adjustment of said variable condensers through a limited tuning range, the inductance in one of said circuits being greater 115 than the inductance in the other. 120

4. A superheterodyne receiver for telephone signals, comprising a receiving circuit including an inductance and a variable condenser, a local oscillation circuit coupled to the receiving circuit including an inductance, a fixed condenser and a variable condenser connected in series, the capacities of said variable condensers being equal and said variable condensers being equally adjusted by one 125 130

control means, said fixed and variable condensers having such relative values that an intermediate beat frequency of approximately constant value is produced as the receiving circuit is tuned to an incoming signal by said control means, the ratio between said inductance having a value other than unity.
